UNITED STATES PATENT OFFICE.

JOHN EDWARD HERMAN, OF SANDUSKY, OHIO.

DESIGN FOR AN ANTIGLARE SHIELD FOR A MOTOR VEHICLE.

Application filed June 23, 1926. Serial No. 18,156. Term of patent 14 years.

To all whom it may concern:

Be it known that I, JOHN EDWARD HERMAN, a citizen of the United States, residing at Sandusky, in the county of Erie and State of Ohio, have invented a new, original, and ornamental Design for an Antiglare Shield for a Motor Vehicle, of which the following is a specification, reference being had to the accompanying drawings, forming part thereof.

In said drawings, Figure 1 is a face view of an antiglare shield showing my new design. Fig. 2 is an end view of said shield. Fig. 3 is a top plan in relation to Fig. 1.

I claim:

The ornamental design for an antiglare shield for a motor-vehicle, as shown.

JOHN EDWARD HERMAN.
